UNITED STATES PATENT OFFICE.

ARMAND H. PEYCKE, OF CHICAGO, ILLINOIS, ASSIGNOR TO AMERICAN STEEL
FOUNDRIES, OF CHICAGO, ILLINOIS, A CORPORATION OF NEW JERSEY.

EQUALIZER MECHANISM.

1,323,315.

Specification of Letters Patent.

Patented Dec. 2, 1919.

Application filed May 15, 1918. Serial No. 234,574.

To all whom it may concern:

Be it known that I, ARMAND H. PEYCKE, a citizen of the United States, residing at Chicago, in the county of Cook and State 5 of Illinois, have invented certain new and useful Improvements in Equalizer Mechanism, of which the following is a specification.

This invention relates to equalizer mechanism.

One object of this invention is to prevent interference between brake mechanism and car under structure in rounding short curves.

Another object is to provide an equalizer 15 mechanism adapted to meet requirements for extreme service conditions.

These and other objects are accomplished by means of the arrangement disclosed on the accompanying sheets of drawings in 20 which,

Figure 1 is a fragmentary plan view of brake equalizer mechanism, arranged in accordance with my invention.

Fig. 2 is a fragmentary side elevation of 25 the same.

Fig. 3 is a detail sectional view, taken in the plane of line 3—3 of Fig. 1.

Fig. 4 is a perspective view of the arrangement disclosed in Figs. 1 and 2, and 30 Fig. 5 is a perspective view of a modification of my invention.

The various novel features of my invention will be apparent from the following description and drawings and will be particularly pointed out in the appended claims.

Referring to Figs. 1 to 4, inclusive, it will be noted that I have shown a truss type of 40 brake beam having a tension member 10 and a compression member 11, there being brake heads 12 at the end of the beam carrying break shoes 13 for frictionally engaging the braking surfaces of associated truck wheels 14. Hangers 15 are connected to the brake head for supporting the brake beam and associated parts. Interposed between the tension and compression members 10 and 11, is a fulcrum 16 to which is pivotally connected the lower end of a brake lever 17 to the upper end of which is connected a link 18 45 which in turn is pivotally connected to one end of a main equalizing bar 19. To the other end of the main equalizing bar 19 is pivotally connected a pull rod 20, there being an associated pull rod 21, which is piv-

totally connected to an intermediate portion 55 of the brake lever 17.

In some types of cars, it is found that where a body pull rod is connected to the main equalizing bar, the brake pull rods and other associated parts interfere with the under structure of the car in rounding short curves, sometimes resulting seriously. More specifically stated, if the body pull rod is connected directly to the main equalizing bar, a force is developed tending to pull the 65 rigging to one side or the other when rounding curves. To overcome this undesirable feature I have connected an auxiliary equalizing bar 20' to the main equalizing bar by links 21', which extend from the ends of the 70 auxiliary equalizing bar to intermediate portions of the main equalizing bar. Pivotally connected to the auxiliary equalizing bar is a body pull rod 22. By means of this arrangement short curves may be rounded 75 without encountering interference difficulties.

Secured to a cross bar or truck end sill 23 of the car truck is a supported loop member 24 for supporting the main equalizing 80 bar 19 and its associated parts, the main equalizing bar sliding upon the lower portion of the loop member 24. A brake releasing spring 25 is also connected to this frame member 23 for operatively engaging the 85 compression member 11 of the brake beam.

By referring to Fig. 5, it will be noted that I have shown my invention as applied to the bar type of beam 26, having brake levers 27 operatively connected thereto 90 through fulcrums 28, intermediate portions of the brake levers being pivotally connected to pull rods 29 and the upper end of said levers being connected by a main equalizing bar 30. This main equalizing bar is connected to an auxiliary equalizing bar 31 by links 32 and the auxiliary equalizing bar 31 has connected thereto intermediate its ends a body pull rod 33.

There may be other modifications of the 100 invention and it is my intention to cover all such which do not involve a departure from the spirit and scope of the following claims.

I claim:

1. In brake mechanism, the combination of a brake beam, a fulcrum member connected thereto, a brake lever connected to

said fulcrum, a main equalizing bar, a link connection between said lever and one end of said main equalizing bar, a pull rod connected to the other end of said main equalizing bar, and an auxiliary equalizing bar operatively connected to said main equalizing bar.

2. In brake mechanism, the combination of a brake beam, a fulcrum member connected thereto, a brake lever connected to said fulcrum, a main equalizing bar, a link

connection between said lever and one end of said main equalizing bar, a pull rod connected to the other end of said main equalizing bar, an auxiliary equalizing bar, links connecting said main and auxiliary equalizing bars, and a body pull rod connected to said auxiliary equalizing bar. ¹⁵

Signed at Chicago, Illinois, this 9th day of May, 1918.

ARMAND H. PEYCKE.
